UNITED STATES PATENT OFFICE.

GRIFFITH W. WILLIAMS, OF GREENSBURG, INDIANA.

WIRE-STRETCHER.

SPECIFICATION forming part of Letters Patent No. 393,410, dated November 27, 1888.

Application filed August 2, 1888. Serial No. 281,779. (No model.)

To all whom it may concern:

Be it known that I, GRIFFITH W. WILLIAMS, a citizen of the United States, residing at Greensburg, in the county of Decatur and State of Indiana, have invented new and useful Improvements in Wire-Stretchers, of which the following is a specification.

The invention relates to improvements in wire-stretchers; and it consists in the construction and novel combination of parts hereinafter described, illustrated in the drawings, and pointed out in the appended claim.

Figure 1 of the drawings represents a perspective view of a wire-stretching device embodying the invention. Fig. 2 represents a vertical section thereof through the pawl-recess.

Referring to the drawings by letter, A designates the bearing-plate of the stretcher, having the concave edge *a*, and provided on each side of said edge with the outstanding lateral ears *B*, in the outer edges of which are the semicircular bearing-notches *b*.

b' b' are screw-openings through which the bearing-plate may be attached to a suitable support—as, for instance, a post. Adjoining the inner side of the said ears is the flanged recess *D*, the floor of which inclines downward or inward from the concave edge *a*. The said recess is adapted to receive the foot *e* of the removable dog or pawl *E*, the beveled engaging-point *e'* of which faces the concave edge *a* of the bearing-plate, and the arm *e''* of which inclines downward and away from said edge and tends to throw the point of the pawl upward.

F is the roller, provided with a diametrical opening, *I*, for the attachment of the wire to be stretched, and with the journals *f*, which rest in the bearing-notches *b*. *G* is a ratchet-wheel on said roller, provided with teeth *g*,

the shoulders of which face the beveled point *e'* of the pawl, and *H* is a squared portion of the roller on the outer side of the said wheel and bearing *b* on the same side and adapted to enter the eye of a crank-handle. The wire is attached to the roller through the diametrical opening therein and by means of the crank-handle wound thereupon and stretched. The wire in leaving or winding upon the roller passes through the concavity of the edge *a*, so that the strain is always toward the bottom of the bearings *b*, and will consequently hold the journals *f* therein. The point of the pawl or dog engages the teeth of the ratchet-wheel at the lower edge of the latter. Consequently in whatever direction the wire may be pulled the said point will not act as a fulcrum to aid in lifting the journals of the roller from the bearing-notches *b*. The arm *e''* of the pawl tends to cause the point of the latter to engage the ratchet-wheel by gravity, and may be pressed inward to release the pawl when it is necessary to loosen the wire or relieve the strain thereon.

Having described my invention, I claim—
The improved wire-stretcher comprising the bearing-plate having the concavity *a*, the notched ears *B*, and the flanged recess *D*, the pawl *E*, having the foot *e*, resting in said flanged recess, the beveled point *e'*, and the downwardly-inclined arm *e''*, the roller *F*, journaled in the notched ears *B*, and the ratchet-wheel on the roller engaged by the point *e'* of the pawl, as set forth.

In testimony that I claim the foregoing as my own I have hereto affixed my signature in presence of two witnesses.

GRIFFITH W. WILLIAMS.
